UNITED STATES PATENT OFFICE.

ISIDOR KITSEE, OF PHILADELPHIA, PENNSYLVANIA.

TELEPHONY.

SPECIFICATION forming part of Letters Patent No. 745,019, dated November 24, 1903.

Application filed March 7, 1901. Serial No. 50,232. (No model.)

To all whom it may concern:

Be it known that I, ISIDOR KITSEE, a citizen of the United States, and a resident of the city and county of Philadelphia, State of Pennsylvania, have invented certain new and useful Improvements in Telephony, of which the following is a full, clear, and complete disclosure.

My invention relates to improvements in telephony, and involves particularly those parts of telephone systems located at the central exchanges, especially switchboards and their accessories, for making connections between different subscribers' stations.

The object of my invention is to facilitate the connecting of two subscribers' circuits, doing away with the well-known inconvenient and cumbersome "cord-circuits" or cord connections, thereby reducing the number of operations necessary in making connections and at the same time making many of said operations automatic in their action.

For a full, clear, and exact description of my invention reference may be had to the following specification and to the accompanying drawings, forming a part hereof, in which—

Figure 1 is a diagram of my improved telephone system, showing two subscribers' stations, their corresponding plugs, and four movable connecting-plates in each board. Fig. 2 is a view of the boards or panels comprised in one operator's set. Fig. 3 is a vertical section through one of the plug-switches.

Fig. 4 is an elevation of one of the plug depressors or keys. Fig. 5 is a horizontal sectional view taken above one of the movable plates of the call-board. Fig. 6 is a diagrammatic view of one plug-switch each of the calling-board and the distributing-board, showing two subscribers' stations connected thereto, respectively, and showing the parts in the position just after No. 1's plug has been depressed, but before the plate was moved toward its operating-magnet. Fig. 7 is a similar view showing both plugs depressed and the call-bell of No. 2 being rung, and Fig. 8 is a similar view showing both stations connected for conversation.

50 A represents what I term a "call-board"—that is, a board to which the calls are pri-

marily sent and in the leads to which from each station a "drop" or other annunciator may be inserted to call the attention of the operator. B indicates a "distributing-board"— 55 that is, the board from which the call is sent to the station desired to be connected to a station which has called up through the call-board. It is obvious that each outlying station must have a plug-switch in both the call-board and the distributing-board in order to allow of any station being connected with any other. Since one operator cannot attend to all the plugs or lines in one switchboard, the call-boards are divided into sections, each 60 consisting of a suitable number of plugs to be easily taken care of by one operator. Several of these sections of the call-board may be placed opposite one distributing-board and the latter may be duplicated until there 65 is room for all the sections of the call-board. This arrangement does not differ from those in the well-known central-station practice of the present day. Fig. 2 shows one section of the call-board and its corresponding distributing-board. In this instance there would 70 be six sections of the call-board to correspond to one distributing-board. The call and distributing boards may be placed in the same vertical frame; but this is not essential, as 75 they may be placed according to choice and convenience.

My improved connecting or switch boards are especially applicable to be used with the so-called "central-energy" telephone systems 85 or those where a closed circuit is maintained to each telephone-station when the same is not in use, although they may be adapted to be used with other systems.

C and C' are contact-plates which are located at the limit of the outward movement of the plug E and are connected, respectively, with the poles of a common main battery T. The plug E is preferably of non-conducting material and is surrounded by the semicylindrical halves of the plug-socket D and D', to each of which is connected one of the leads from a telephone-station. The plug E has an extension E', which passes through an opening in the fixed plate F and is adapted in connection with the parts D and D' of the plug-socket to form a guide for the plug E. A

spring E², interposed between the plate F and the bottom of the plug E, acts to return the plug to its normal or inoperative position.

5 G is a longitudinal contact carried by the plug E, which is adapted to form an electrical connection between the parts C' and D' when the plug is in its normal or inoperative position.

H is a fixed plate of conductive material 10 and is located adjacent the ends of the plug-sockets, so that when the plug is depressed the contact G will make electrical connection between the same and the part D', as shown in Fig. 6.

15 I is a contact carried by the plug E, which is always in contact with the part D of the plug-socket and connects said part D with the part C when the plug is in its normal position.

20 J J, &c., are conductive plates or frames, so connected as to be operative in pairs, one plate of each pair being located in the call and distributing boards, respectively, and have slots J' formed therein, through which the 25 plugs E are adapted to pass. These plates are insulated from each other and are carried by rollers J² or other suitable antifriction devices. They are held in their normal or inoperative positions by suitable springs J³.

30 The plates J correspond to the cord connectors in the cord-circuit systems and are of a similar number—to wit, about ten per cent. of the number of stations connected to any one panel of a switchboard. The slots in the 35 plates J are of sufficient length to allow either one of the pawls K or L to pass therethrough in either direction, according to whether a plate is in its operative or inoperative position.

The pawls K and L have insulating-40 strips K⁵ and L² upon one side thereof, respectively, so that in passing the plates J in one direction no electrical contacts are made therewith. The pawl L is held in its normal raised position by the spring-arm L', and the 45 pawl K is adapted to rest upon the spring-arm K⁴ by gravity when in its lower or inoperative position.

K² is a pin or projection carried by the pawl K and is adapted to contact with the 50 upper edge of the pawl L, so that when the pawl L is raised K will be depressed and when K is raised L will be depressed. These pawls K and L are pivoted upon a pin K', which has electrical connection with the contact I by means of the wire I'. When the 55 plug E is depressed, the pawl K will engage the first plate which is not already in use to make a connection. This is due to the fact that the slots J' are so located that when the

60 plates J are moved by their magnets one end of the slot will come into alinement with the end of the pawl K and allow the same to pass without interruption. The pawl K will therefore engage the first plate which is not in use, 65 and as the inward movement of the plug E is continued the pawl K will be raised, thereby

depressing and extending the pawl L. At the same time the uninsulated part of the pawl K will contact with the plate and make a connection, as illustrated in Fig. 6, to energize a magnet N to draw the plate into its operative position. As the plate J is drawn over, the plate at the opposite end of the slot passes over the end of the pawl L, which has been depressed, thereby making a second 75 contact with the uninsulated part of the same, which maintains the action of the magnet N first energized, while at the same time the pawl K is allowed to drop into its original position. The magnet N is energized by the 80 battery V, the current passing through the armature O', (hereinafter to be more particularly described,) contact P, magnet N, plate J, pawl L, wire I', contact I, and contact D 85 to battery V.

O' is an armature which is pivoted at O², so as to be normally in contact with the point P, and is retained in that position by the arm J⁴, which in the plates of the call-board is insulated, but in the distributing-board is electrically connected with the plate J. A clearing-out magnet O acts upon the armature O' to withdraw it from the point P when the arm J⁴ allows it to do so by reason of the movement of the plate J. The magnets O are 95 electrically connected in pairs corresponding to the pairs of plates in the call and distributing boards and not energized until both receivers are off their hooks at the calling and the called telephones. This is made possible 100 from the fact that the leads 2^a and 2^b are connected to the parts D and D' in each board, respectively, which will allow the current to pass through the contacts I, wires I', pawls L, plates J, magnets N, and magnets O. In 105 the distributing-switchboards the arms J⁴ contact with points Q when the plates are attracted by the magnets. These points Q are connected to ground S through the battery R.

U is a battery each pole of which is connected with the plates H in the call and distributing boards, respectively.

Each telephone-station is provided with the usual contacts, consisting of the points f and g, which are adapted to be engaged by the receiver hook-lever d, the point g being connected to ground j through the vibrating call-bell i.

Operation: Supposing a call has been made from the station No. 1, the plug E in the call-board is then depressed, thereby putting the pawl L in contact with the plate J, which is attracted by the magnet N, as above described. The operator at the call-board then ascertains from the subscriber at station No. 1 what other station he wishes to converse with and thereupon depresses the plug corresponding to that station in the distributing-board. This is the condition supposed to exist in Fig. 7. When the plug E in the distributing-board is depressed, the disengaged plate J, corresponding to the plate J just op-

erated in the call-board, is connected with the plug and its corresponding magnet N energized. The arm J⁴ then contacts with the point Q, thereby closing a circuit from battery R through ground S, ground j, bell i, contact g, lever d, lead 2^b, part D, contact I, wire I', pawl L, plate J to arm J⁴ and contact Q. The bell at station No. 2 is therefore kept ringing until the call is answered and the receiver h is lifted from its hook lever d. When this is done, both magnets O are energized and the armatures O' withdrawn from the points P, as shown in Fig. 8. Both telephone instruments are then connected together through the battery U by a circuit passing through the plate H of the distributing-board, contact G, part D', lead 1^b, lead 2^b, part D, contact I, wire I', pawl L, plate J, magnet N, magnet O, magnet O' of the call-board, magnet N, plate J, pawl L, wire I', contact I, part D, leads 2^a and 1^a, part D', contact G, plate H to battery U. Both stations are therefore connected for talking and remain in that condition until one of the receivers is replaced on its hook, thereby breaking the circuit through both pairs of magnets N and O, which returns the plates J and plugs E to their normal positions. When in their normal positions, the plugs E connect the battery T with the leads from the stations through the parts C, I, D, and C', G, and D', thereby keeping the lines constantly energized.

The station annunciators or calls and the operators' telephones may be connected with the line-terminals in any well-known way which will be self-suggestive to one skilled in the art, and I have not shown the same, as they form no part of my invention and their omission simplifies the description.

Changes may be made in the form and arrangement of parts without separating from the spirit and scope of my invention; but

What I claim, and desire to protect by Letters Patent of the United States, is—

1. An exchange for telephone systems comprising switchboards, line-terminals in said boards, connections between said boards and means independent of each other located within said boards at each terminal for connecting any of said terminals with corresponding ends of said connections.

2. An exchange for telephone systems comprising switchboards, line-terminals in said boards, connections between said boards, slideable contacts for said connections and means independent of each other located within said boards at each terminal for connecting any of said terminals with corresponding slideable contacts in each board.

3. An exchange for telephone systems, comprising, a call-board, a distributing-board, line-terminals in each board, connections between the boards and independent means within said boards at each terminal for connecting said terminals and any of said connections.

4. An exchange for telephone systems, com-

prising, a call-board, a distributing-board, line-terminals in each board, connections between the boards, and independent means at each terminal for connecting said terminals and any of said connections.

5. An exchange for telephone systems, comprising, a call-board, a distributing-board, line-terminals in each board, connections between the boards, slideable plates, and independent means adjacent each terminal for connecting said terminals and said slideable plates.

6. An exchange for telephone systems, comprising a call-board, a distributing-board, line-terminals in each board, connections between the boards and independent movable parts within said boards at each terminal for connecting said terminals and said connections.

7. An exchange for telephone systems, comprising a call-board, a distributing-board, line-terminals in each board, connections between the boards, said connections having slideable contacts adjacent the line-terminals in each board and independent means corresponding to each terminal for connecting said terminals and said slideable contacts.

8. An exchange for telephone systems comprising, a call-board, a distributing-board, line-terminals in each board connections between the boards, said connections having contacts adjacent the line-terminals in each board and independent movable parts in permanent connection with each pair of terminals for connecting said terminals and said contacts.

9. An exchange for telephone systems comprising, a call-board, a distributing-board, line-terminals in each board, connections between the boards, said connections having slideable contacts adjacent all the line-terminals in each board and independent movable parts in permanent connection with each terminal for connecting said terminals and said contacts.

10. An exchange for telephone systems comprising a call-board, a distributing-board, line-terminals in each board, connections between the boards, each connection having contacts in each board a part of each contact being adjacent every terminal in its corresponding board, means for rendering each contact inoperative in regard to every terminal except one, and movable parts in connection with each terminal for connecting said terminals and said contacts.

11. An exchange for telephone systems comprising, a call-board, a distributing-board, line-terminals in each board, connections between the boards, each connection having contacts in each board, movable parts in connection with each terminal, and means for automatically connecting said terminals with any one of said contacts which is not in use.

12. An exchange for telephone systems comprising, a call-board, a distributing-board, line-terminals in each board, connections be-

tween the boards each having contacts which are adjacent every terminal in each board, movable parts in connection with each terminal, and means for automatically selecting one of said contacts which is not in use and connecting the same with its terminal.

13. An exchange for telephone systems comprising, a call-board, a distributing-board, line-terminals in each board, connections between the boards, each connection having slideable plates in each board, a part of which is adjacent every terminal in each board, movable parts in permanent connection with each terminal, and means for automatically selecting one of said plates and connecting the same with its terminal.

14. An exchange for telephone systems comprising, a call-board, a distributing-board, line-terminals in each board, connections between the boards, slideable plates in each board corresponding to each board, movable parts in permanent connection with each terminal, means for automatically selecting one of said plates to connect the same with its terminal, and electromagnetic means included in said connections for holding said plates in operative contact with said movable parts.

15. In an exchange for telephone systems, switchboards, line-terminals connected to said boards, independent permanent conductors in proximity to and connecting said boards, automatic gripping devices located within said boards, and movable parts for operating said gripping devices, in combination with means to automatically release said conductors from said gripping devices.

16. An exchange for telephone systems comprising switchboards, line-terminals of the calling subscribers, line-terminals of the subscribers to be called each connected to said boards, independent permanent conductors in proximity to and connecting said boards, holes or perforations in said boards for each of said terminals, means located in each of said holes or perforations to connect automatically said terminals with any of said independent conductors, movable parts for operating said means, and automatic means to release said connecting means.

17. In an exchange for telephone systems, call and switch boards, a series of movable plates in each board, connections between pairs of said plates, automatic gripping devices within said boards adapted to select and grip such of said plates as are not in use, means for operating said gripping devices, and automatic releasing devices adapted to release the gripped plates.

18. An exchange for telephone systems comprising switch-boards, line-terminals of the calling subscribers and line-terminals of the subscribers to be called connected to said boards, independent permanent conductors in proximity to and connecting said boards, automatic gripping devices connected to each of said terminals adapted to connect said terminals with any of said independent conductors, means for operating said gripping devices, and automatic means to disconnect said gripping devices from said conductors.

19. An exchange for telephone systems comprising, a call-board, a distributing-board, line-terminals in each board, connections between the boards, each connection having movable contacts in each board a part of each contact being adjacent every terminal in its corresponding board, and movable parts in connection with each terminal for connecting said terminals with any of said contacts.

20. An exchange for telephone systems comprising, a call-board, a distributing-board, line-terminals in each board, connections between the boards, each connection having slideable contacts in each board, a part of each contact being adjacent every terminal in its corresponding board, means for sliding said contacts and holding them in position, and movable parts in connection with each terminal for connecting said terminals with any of said sliding contacts.

21. An exchange for telephone systems comprising, a call-board, a distributing-board, line-terminals in each board, connections between the boards, slideable frames or plates in each board for each connection, a part of each frame or plate being adjacent every terminal in its corresponding board, means for sliding said frames and for holding them in operative or inoperative position, and slideable plugs in connection with each terminal for connecting said terminals with any of said frames or plates.

22. An exchange for telephone systems comprising, a call-board, a distributing-board, line-terminal in each board, plug-sockets for each terminal, a plug for each socket, fixed conductors having parts adjacent each of said plugs, a battery connected between said conductors, a slideable contact carried by each plug adapted to connect one of said conductors and a plug-socket, pawls carried by each plug, a series of slideable conductive plates adapted to be engaged by any of said pawls, connections between the plates of the different boards, magnets controlled by said pawls for drawing said plates into operative position, electromagnetic clearing-out devices also controlling said magnets, projections carried by each slideable plate to render said clearing-out devices inoperative when said plates are in their normal positions, contacts in the distributing-board adapted to engage said projections and thereby close a ground-circuit and batteries in said ground-circuit.

In testimony whereof I hereby sign my name, in the presence of two subscribing witnesses, this 28th day of January, A. D. 1901.

ISIDOR KITSEE.
